Paula de Pontrex, New York, N. Y., assignor to Pinaud Incorporated, New York, N. Y., a corporation of New York

Application May 3, 1943, Serial No. 110,099

Term of patent 7 years

To all whom it may concern:

Be it known that I, Paula de Pontrex, a citizen of the United States of America and a resident of New York, N. Y., have invented a new, original, and ornamental Design for a Combined Boutonniere and Perfume Container, of which the following is a specification, reference being had to the accompanying drawing, forming part thereof.

The drawing illustrates a front elevational view slightly in perspective of a combined boutonniere and perfume container showing my new design.

I claim:

The ornamental design for a combined boutonniere and perfume container, as shown.

PAULA DE PONTREX.
